SIGNALING DEVICE FOR SPINNING FRAMES

Joseph F. Hunt, Augusta, Ga.

Application November 7, 1949, Serial No. 125,870.

4 Claims. (Cl. 116—132)

1

My invention relates to a visual signal device for spinning frames.

An important object of the invention is to provide a highly simplified signal device for indicating the condition of the spinning frame, such as when one or more tapes are off or one or more broken back ends or yarns are present.

A further object of the invention is to provide a signal device of the above mentioned character which is adjustable so that it occupies a conspicuous position in use, and may be shifted to an out of the way position, when not in use.

A further object of the invention is to provide a device of the above mentioned character formed of few and simple parts which may be readily assembled and separated.

Other objects and advantages of the invention will be apparent during the course of the following description.

In the accompanying drawings, forming a part of this application, and in which like numerals are employed to designate like parts throughout the same,

Figure 1 is a transverse vertical section through the creel of a spinning frame showing my signaling device mounted thereon,

Figure 2 is a plan view of the creel, parts broken away,

Figure 3 is a fragmentary side elevation of the creel, showing the signal device applied thereto,

Figure 4 is a side elevation of a signal device embodying my invention, showing the flag in the raised vertical position,

Figure 5 is a similar view, showing the flag in the lowered vertical position,

Figure 6 is a similar view, showing the flag in the retracted horizontal position,

Figure 7 is a bottom plan view of the signal device, showing the flag in the lowered vertical position,

Figure 8 is a side elevation of the flag viewed from the opposite side with respect to Figure 5,

Figure 9 is a transverse section taken on line 9—9 of Figure 4, and

Figure 10 is a similar view taken on line 10—10 of Figure 6.

In the drawings, where for the purpose of illustration is shown a preferred embodiment of my invention, the numeral 10 designates a creel of a spinning frame, beneath which are mounted for rotation on vertical axes the usual bobbins 10'. As shown clearly in Figure 2, the bobbins 10' are arranged in longitudinal rows, and there is a relatively small space between adjacent bobbins in each row. The rows of bobbins 10' extend for

2

substantially the entire length of the creel 10, as is well known. The top of the creel 10 forms a shelf for use in storing the bobbins 10', as is well known. Arranged beneath the creel 10 are signal devices 11 embodying my invention.

The signal devices 11 are mounted upon the bottom of the creel 10 and extend transversely of the creel, as shown. The signal devices are arranged between adjacent pairs of the bobbins 10'.

Each signal device comprises a horizontal sleeve 12, having a top 13 provided at its ends with apertured ears 14 to receive screws 15, which secure the ears to the lower face of the creel 10. The sleeves are arranged in a pair which extends transversely of the creel inwardly of and near its longitudinal edges. Each sleeve is substantially cylindrical, with the top 13 somewhat flattened. The sleeve 12 has a longitudinal slot 14' formed in one side thereof extending through its opposite ends. At one end, the sleeve 12 has a longitudinal notch or short slot 16 formed therein, at the bottom of the sleeve, and the sleeve is provided at its opposite end with a longitudinal notch or short slot 17, at the side of the sleeve and spaced 90° from the notch 16.

The numeral 18 designates a cylindrical rod which is loosely mounted within the sleeve 12 and is free to move longitudinally and turn therein. The rod 18 is substantially longer than the sleeve 12 so that the forward end of the rod may be shifted to a point beyond the adjacent longitudinal edge of the creel 10, Figure 1, while the rear end of the rod is adjacent to the rear end of the sleeve. This rod is provided at its outer end with a stiff flag or plate 19, rigidly secured to the rod by rivets 20 or the like at one longitudinal edge portion of the flag. The flag or plate 19 may be formed of metal, plastics, or any other suitable material. The flag may be painted a suitable color, such as yellow or red. The opposite faces of the flag are used for producing visual signals. Each face of the flag has a horizontal dividing line and radially outwardly of this dividing line each face is equipped with letters "TP," designated at 22, indicating that one or more tapes are off. These letters are printed to be read in the upright position when the flag 19 is in the vertical raised position. In the space radially inwardly of the line 21, each face of the flag has printed thereon at 23, letters "BB," indicating that the spinner has broken back one or more ends that need fixing. The letters "BB" are arranged to be read in the upright position when the flag is in the lowered vertical position. The letters 22 upon opposite faces of the flag are reversed, and the letters 23

50

55

upon opposite faces are reversed, and the letters 22 and 23 upon each face are superposed.

The rod 18 carries a radial pin 24 rigidly secured thereto and this pin extends radially upon the same side of the rod 18 with the flag 19 and is in alignment with this side. The rod 18 has a pin 25 rigidly secured to its free end and this pin extends radially in an opposite direction to the pin 24 and is disposed 180° from the pin 24.

When the signal device is in use, the flag 19 is shifted outwardly beyond the longitudinal edge of the creel 10. If it is desired to signal that there are broken back ends, which need fixing, then the flag 19 in the outer position is also moved to the lowered vertical position and the letters 23 will indicate this condition. These letters may be read from the opposite faces of the flag. The flag will stay in this vertical lowered position by gravity. When it is desired to signal that one or more tapes are off, the flag is swung to the raised vertical position and the pin will enter the notch 16, when the rod 18 is shifted outwardly slightly, Figure 4. The flag 19 is now locked in the raised vertical position and the letters 22 may be read from both faces of the flag. When the signalling device is not in use, the rod 18 is moved inwardly longitudinally and is turned upon its longitudinal axis so that the pin 24 may enter the notch 17. The rod 18 is now locked in this position and the flag 19 arranged horizontally beneath the creel 10 and held in such horizontal position, inwardly of the adjacent longitudinal edge of the creel 10. The longitudinal slot 14' is provided so that the pin 25 may pass through the sleeve 12 in assembling the device.

The arrangement is such that the operator can manipulate the flag 19 from the forward end of the rod 18. This is necessary since there is not sufficient space between the bobbins 10' for the operator to pass his hand adjacent to either side of the sleeve 12. The arrangement of the notches 16 and 17 for coaction with the pins 24 and 25 makes it possible to shift the flag to all operative positions by grasping the forward end of the flag and no other part of the device.

It is to be understood that the form of my invention herewith shown and described is to be taken as a preferred example of the same, and that various changes in the shape, size and arrangements of parts may be resorted to without departing from the spirit of the invention or the scope of the subjoined claims.

Having thus described my invention, I claim:

1. A signal device to be applied to the creel of a spinning frame, said device comprising a sleeve arranged beneath and secured to the creel, said sleeve having a longitudinal slot extending throughout its entire length, said sleeve being provided at one end and at its bottom with a notch and provided at its opposite end and at its side with a notch disposed at substantially 90° from the bottom notch, a rod mounted within the sleeve to move longitudinally and turn therein and being substantially longer than the sleeve, a flag secured to one end of the rod and extending radially thereof, said flag being provided upon each of its opposite faces with indicia indicating the condition of the spinning frame, one indicium being inverted with respect to the other indicium, a first pin secured to the rod near the flag and extending radially in the direction of the flag, and a second pin secured to the rod near the free end of the rod and extending radially in an opposite direction to the first pin, the second pin

being adapted to enter the bottom notch when the rod is turned to bring the flag to the raised vertical position, the flag being turned to the lowered vertical position when the second pin is moved out of the bottom notch, the first pin being adapted to be moved into the side notch when the rod is shifted longitudinally inwardly and turned so that the flag is substantially horizontal, the pins being passable through the longitudinal slot to permit complete separation of the rod and flag from the sleeve.

2. A signal device to be applied to the creel of a spinning frame comprising a sleeve arranged beneath and secured to the bottom of the creel 15 in a substantially horizontal position, the sleeve extending transversely of the creel and having forward and rear ends, the forward end of the sleeve being spaced laterally inwardly of one longitudinal edge of the creel, the sleeve having 20 a notch in its rear end remote from the longitudinal edge of the creel, a rod mounted within the sleeve for longitudinal and turning movement and being substantially longer than the sleeve so that the forward end of the rod may be 25 positioned near the longitudinal edge of the creel while its rear end is adjacent to the rear end of the sleeve, a flag plate of substantial weight having one longitudinal edge portion secured to the rod near the forward end of the rod and extending 30 radially of the rod, a radial element secured to the rod near its rear end and adapted to enter the notch and hold the rod against rotation when the rod is shifted forwardly and the flag plate turned to an upstanding vertical position laterally outwardly of the longitudinal edge of the 35 creel, the flag plate indicating one defective condition of the spinning frame when shifted forwardly and to the upstanding vertical position and another defective condition when shifted forwardly and to a depending vertical position with the radial element disengaged from the notch, gravity holding the flag plate in the depending vertical position while the radial element is disengaged from the notch, the rod being shiftable 40 rearwardly longitudinally in the sleeve until the flag plate is retracted beneath the creel and inwardly of its longitudinal edge with the rear end of the rod projecting a substantial distance rearwardly of the rear end of the sleeve, and means 45 for holding the flag plate in a substantially horizontal position while it is retracted beneath the creel.

3. A signal device to be applied to the creel of a spinning frame comprising a sleeve arranged 55 beneath and secured to the creel in a substantially horizontal position, the sleeve extending transversely of the creel and having forward and rear ends, the sleeve having a longitudinal slot extending throughout its entire length, the sleeve 60 being provided in its forward end with a first notch and in its rear end with a second notch spaced circumferentially of the first notch, a rod mounted within the sleeve for longitudinal and turning movement and being longer than the 65 sleeve so that the rod may have its forward end positioned near the adjacent longitudinal edge of the creel while its rear end is near the rear end of the sleeve, a flag plate of substantial weight having one longitudinal edge portion secured to the 70 rod near the forward end of the rod and extending radially of the rod, a first radial pin secured to the rod near the flag plate, and a second radial pin secured to the rod near its rear end and spaced circumferentially of the first pin, the 75 circumferential spacing of the pins and notches

being such that when the rod is shifted forwardly and the second pin enters the second notch the rod is held against turning with the flag plate disposed in an upstanding vertical position outwardly of the adjacent longitudinal edge of the creel, the flag plate maintaining a depending vertical position by gravity when the second pin is disengaged from the second notch, the first pin entering the first notch when the rod is shifted longitudinally rearwardly and holding the rod against turning with the flag plate arranged substantially horizontally, the second pin being passable forwardly through the longitudinal slot to permit complete separation of the rod and flag plate from the sleeve.

4. A signal device to be applied to the creel of a spinning frame comprising a sleeve for arrangement beneath the creel in a substantially horizontal position and extending transversely of the creel and having forward and rear ends, apertured extensions carried by the forward and rear ends of the sleeve and disposed at the upper side of the sleeve and secured to the bottom of the creel, the sleeve having a side longitudinal slot extending throughout its entire length, the sleeve being provided in its forward end with a first notch and in its rear end with a second notch spaced circumferentially of the first notch, a rod mounted within the sleeve for longitudinal and turning movement and being substantially longer than the sleeve so that the rod may have its forward end positioned near the adjacent longitudinal edge of the creel while its rear end is near the rear end of the sleeve, a flag plate of substantial

weight having one longitudinal edge portion secured to the rod near the forward end of the rod, the flag plate extending radially of the rod, a first radial pin secured to the rod near the flag plate, and a second radial pin secured to the rod near its rear end and spaced circumferentially of the first pin, the circumferential spacing of the pins and notches being such that when the rod is shifted forwardly and the second pin enters the second notch the rod is held against turning and the flag plate is disposed in an upstanding vertical position outwardly of the longitudinal edge of the creel, the flag plate maintaining a depending vertical position by gravity when the second pin is disengaged from the second notch, the first pin entering the first notch when the rod is shifted rearwardly and holding the rod against rotation with the flag plate arranged substantially horizontally, the second pin being passable forwardly through the side longitudinal slot to permit complete separation of the rod and sleeve.
